UNITED STATES PATENT OFFICE.

HUGH D. MORGAN, OF YOUNGSTOWN, OHIO.

MEANS FOR ATTACHING AN ARTIFICIAL TOOTH TO A BACKING OR BRIDGE PLATE.

1,261,737.

Specification of Letters Patent. Patented Apr. 2, 1918.

Application filed June 30, 1917. Serial No. 177,924.

To all whom it may concern:

Be it known that I, HUGH D. MORGAN, a citizen of the United States, and a resident of Youngstown, in the county of Mahoning and State of Ohio, have invented a new and Improved Means for Attaching an Artificial Tooth to a Backing or Bridge Plate, of which the following is a full, clear, and exact description.

10 My invention has for its object to provide an artificial tooth with a pin or pins having heads the sides of which diverge outwardly from the artificial tooth, the pins being adapted to be disposed in slots in the 15 backing or bridge plate, the sides of the said slots converging from the cutting edge of the backing or bridge plate, and being under-cut to permit the insertion of the heads of the pins in the slots adjacent the 20 cutting edge and the movement of the artificial tooth into place, the heads of the pins being wedged between the converging sides of the slots during this movement, and the artificial tooth being raised over a tip 25 of the backing or bridge plate at its cutting edge, the said tip protecting the biting edge of the artificial tooth and serving to assist in preventing the outward movement of the artificial tooth.

30 Additional objects of the invention will appear in the following specification in which the preferred form of the invention is disclosed.

In the drawings similar reference characters denote similar parts in all the views, in which—

Figure 1 is an elevation showing an artificial tooth secured to the backing;

Fig. 2 is a view showing the front face of 40 the backing or bridge plate, the pin being illustrated in section;

Fig. 3 is a sectional view on the line 3—3 of Fig. 1;

Fig. 4 is a sectional view on the line 4—4 45 of Fig. 1;

Figs. 5 and 6 are views showing a modified form of the invention;

Figs. 7, 8 and 9 are sectional views showing how a replacement may be made regardless of the length of the tooth; and

Fig. 10 is a sectional view showing a modified form of the invention.

By referring to the drawings, it will be seen that a backing or bridge plate 10 is 55 provided with a slot 11, the sides of which are under-cut as shown by the dotted lines

12, the said sides converging away from the cutting edge 13 of the backing or bridge plate 10. By referring to Fig. 4 of the drawings, it will be seen that this cutting 60 edge 13 of the backing or bridge plate 10 extends forwardly to form a seat for the biting edge 14 of a facing or artificial tooth 15, the said facing or artificial tooth 15 being provided with a pin 16 which is baked 65 in the facing or artificial tooth, the said pin 16 having a head 17 the sides of which diverge outwardly so that the head 17 will fit the under-cut portions of the sides of the slot 11 in the backing or bridge plate 10. 70

The facing or artificial tooth 15 is secured to the backing or bridge plate 10 by disposing the artificial tooth or facing 15 in the position indicated by the dotted lines in Fig. 4 of the drawings, and with the head 75 17 of the pin 16 disposed in the slot 11 at its widest end. In this position the back of the facing or artificial tooth 15 rests against the backing or bridge plate 10 adjacent its cutting edge 13. The facing or 80 artificial tooth 15 is then moved to the position shown by the full lines in Fig. 4 of the drawings, and the head 17 of the pin 16 is wedged between the converging sides 85 of the slot 11. When the pin head 17 is 90 wedged in this position, the biting edge 14 of the facing or artificial tooth 15 rests against the forwardly disposed portion of the backing or bridge plate 10 adjacent its cutting edge.

It will be understood that if desired two of the said slots 11 may be made in the backing or bridge plate 10 and two pins 16, each with a head 17, may be baked in the facing or artificial tooth 15; but whether or not 95 a plurality of slots and pins are employed, the facing or artificial tooth 15 is attached to the backing or bridge plate 10 by the insertion of the heads of the pins in the slots adjacent the cutting edge of 100 the backing or bridge plate, and by moving the facing or artificial tooth relatively to the backing or bridge plate, to wedge the heads of the pins between the sides of the slots and to dispose the biting edge of the 105 facing or artificial tooth against the forwardly disposed portion of the backing or bridge plate.

When a facing or artificial tooth 15 is to be mounted on the backing or bridge plate 110 10, it is merely necessary for the dentist to select a tooth of the desired length to fit the

backing or bridge plate used. When a short tooth is to be used a pin of relatively large diameter is employed, while a smaller pin is used when a larger tooth is to be mounted on 5 the backing or bridge plate. In this way every artificial tooth which is used will have its biting edge disposed at the cutting edge of the backing or bridge plate. Fig. 7 shows a large tooth with a small pin, Fig. 8 shows 10 a medium sized tooth and a medium sized pin, and Fig. 9 shows a small tooth with a large pin. By the selection of the pins the movement of the teeth relatively to the backing is limited as desired for locking 15 purposes.

In Fig. 10 there is shown a modified form 20 of the invention, in which the sides of the undercut slot 10^a are parallel. In this construction liquid cement is employed to assist in holding the facing in place.

Inasmuch as both the backing and the pin are constructed of metal an all-metal back is provided.

Having thus described my invention, I 25 claim as new and desire to secure by Letters Patent:

1. In a means for attaching an artificial tooth to a backing or bridge plate, a backing having a cutting edge, a slot in its face 30 with undercut sides which converge away from its cutting edge, an artificial tooth having a pin with a head of less width than the width of the outer side of the slot at its outer end adjacent the cutting edge, but 35 greater than the width of the outer side of the slot at its inner end, and a shoulder extending forwardly at the cutting edge of the backing over which the facing may be disposed to insert the head of the pin in the 40 outer end of the slot, the shoulder serving to assist in holding the facing in normal position with the head of the pin at the said inner end of the slot when the facing has been moved thereto.

45 2. In a means for attaching an artificial tooth to a backing or bridge plate, a backing having a cutting edge, a slot with undercut sides which converge away from the cutting edge, the under surfaces of the said sides

converging outwardly, a facing and a pin on 50 the facing having a head the sides of which diverge outwardly to fit the undercut sides of the backing.

3. In a means for attaching an artificial tooth to a backing or bridge plate, a backing 55 having a cutting edge, a slot with undercut sides which converge away from the cutting edge, the under surfaces of the said sides converging outwardly, a facing, a pin on the facing having a head the sides of 60 which diverge outwardly to fit the undercut sides of the backing, the head of the pin being greater in width than the outer width of the slot at a point spaced from the cutting edge, and a shoulder extending outwardly at the cutting edge of the backing and which assists in holding the facing with the head of its pin at the said point.

4. In a means for attaching an artificial tooth to a backing or bridge plate, a backing 70 having a cutting edge, there being a slot in the face of the backing with undercut sides which converge away from the cutting edge, an artificial tooth having a pin with a head 75 of less width than the width of the outer side, of the slot at its outer end adjacent the cutting edge but greater than the width of the outer side of the slot at its inner end, the artificial tooth being normally disposed with the head of its pin in the inner end of 80 the slot.

5. In a means for attaching an artificial tooth to a backing or bridge plate, a backing having a cutting edge, there being a slot in the face of the backing with undercut sides, 85 the width of the outer side of the slot at its outer end adjacent the cutting edge being greater than the width of the outer side of the slot at its inner end, an artificial tooth having a pin with a head of less width 90 than the width of the outer side of the slot at its outer end adjacent the cutting edge but greater than the width of the outer side of the slot at its inner end, the artificial tooth being normally disposed against the 95 face of the backing with the head of its pin disposed in the inner end of the slot.

HUGH D. MORGAN.
